Inventor:
Carl Pape,

by *Myron S. Hunt*
His Attorney.

UNITED STATES PATENT OFFICE.

CARL PAPE, OF BERLIN, GERMANY, ASSIGNOR TO GENERAL ELECTRIC COMPANY, A CORPORATION OF NEW YORK.

MAGNETIC CUT-OUT PLUG.

Application filed November 5, 1925, Serial No. 67,138, and in Germany December 17, 1924.

The present invention relates to automatic safety devices for protecting electric circuits and apparatus from injury upon the occurrence of excess flow of current.

5 The general practice, especially in dwelling houses, is to employ fuse plugs for the protection of the electric equipment thereof, but fuse plugs are objectionable in that they are destroyed upon a single operation or 10 blowing thereof and require to be replaced by fresh ones.

15 The object of my invention is the provision of an improved cut-out plug, which shall be capable of an unlimited number of operations and which shall operate definitely to open the circuit in which it is installed at the prescribed overload and without scattering of molten metal.

20 One embodiment of the invention is shown in the accompanying drawing in which Fig. 1 is a vertical axial section of the plug with the parts in the on or closed circuit relation; Fig. 2 is a transverse section taken on line 2—2 of Fig. 1; Fig. 3 is a section similar to 25 that of Fig. 1, but with the parts in the off or open circuit relation; Fig. 4 is a transverse section taken on line 4—4 of Fig. 3, and Fig. 5 is a transverse section taken on line 5—5 of Fig. 3.

30 The base or body part of the plug comprises upper and lower cup-shaped members 1 and 2 of moulded insulation held together by longitudinal screws 3. The lower member 2 has a bottom projection 4 on which are 35 mounted the usual center and screw shell contacts 5 and 6 similar to the usual fuse plug contacts.

Within the cavity of the lower base member 2 and arranged concentrically thereof 40 are a guide bush 7, a coil 8 of magnetic wire, and a magnet armature 9 freely movable longitudinally through the center of the coil 8. Secured within the lower base member 2 above the coil 8 is an insulating disk 10 centrally apertured to provide a guide passage 45 for the armature therethrough and having mounted on its upper surface two stationary switch contacts 11 and 12. One switch contact is connected in well known manner, as 50 by a lead wire to the screw shell contact 6, while the other switch contact is connected to one end of the coil of magnet wire and therethrough to the center contact 5.

The armature 9 carries above the disk 10 55 an insulating head 13 in which is embedded

the movable pole piece 14 of the switch and above the head 13 is a hub 15 with the sides cut away near the end to form a parallel-sided lug 16 at the end. The armature is rotatably biased in a clockwise direction by 60 a clock spring 17 disposed in a central cavity 18 formed in the lower side of the insulating disk 10, whereby the pole piece 14 normally tends to move away from the contacts 11 and 12 and into the position indicated in Fig. 4 against the stops 19 projecting inwardly from the sides of the upper base member 1. The armature is held latched in the on or closed position of the switch by a cross-bar 20 fixed therein which engages the sides of 70 notches 21 extending upwardly from the top of the cavity 18 into the disk 10, and the means for pressing the armature 9 longitudinally upward is a helical spring 22 located between its lower end and the guide block 75 7. This spring is made sufficiently stiff to resist movement of the armature downward under the action of the magnet thereon, while normal current is flowing, but yields upon the occurrence of excess current flow 80 and thereby permits the cross-bar 20 to escape from its retaining notches 21, whereupon the biasing spring 17 causes it to rotate upon its axis to carry the switch pole 85 into off-position.

In order to reset the switch in the on or closed position, the upper body part 2 has swiveled therein a thumbpiece 23 comprising a flanged inner part 24 and an outer thimble-shaped part 25 rigidly attached to the inner 90 part, with a spring 26 interposed therebetween and adapted to frictionally restrain the rotary movement thereof. The flange 27 of the inner part is seated in a circular recess 28 in the inner wall of the upper body part 2, 95 one-half of which is made deeper than the other, as indicated in Figs. 3 and 5, and the flange 27 is provided with a thickened quadrant 29 adapted to play freely in the deepened portion of the recess 28, but limited 100 to a quarter turn therein. The inner part 24 of the thumb-piece has a cylindrical recess 30 adapted to receive the upper end of the hub 15, and extending upwardly as an 105 rectangular mortise 31 adapted to receive therein the end lug 16 whereby the thumb piece 23 may be coupled to the movable switch member.

In Fig. 1 the parts of the plug are shown 110

- in the on or closed relation, while in Fig. 3 they are shown in the open circuit position with the armature 9 and parts carried thereby in lowermost position with the lug 16 pulled clear of the coupling mortise 16 in the thumbpiece 23 so that turning of the thumb piece may not operate to reclose the switch so long as the excess flow of current continues through the magnet coil 8.
- 10 While I have shown and described the best embodiment of the invention known to me, I do not desire to be restricted thereto.
- What I claim as new and desire to secure by Letters Patent of the United States, is:—
- 15 1. A magnetic switch plug comprising a base provided with side and end terminals, a magnet coil concentrically arranged in said base, a notched insulating disk enclosing said coil in said base, switch contacts on said disk, a rotatably biased armature extending through said disk and having provisions for engaging the notches thereof, a movable
- switch member carried by said armature, and a thumb piece extending through said base and provided with means for engaging 25 said movable switch member.
2. A magnetic switch plug comprising a base provided with side and end terminals, a magnet coil concentrically arranged in said base, a notched insulating disk enclosing said coil in said base, switch contacts on said disk, a rotatably and axially biased armature extending through said disk and having provisions for engaging the notches thereof in unretracted position, a movable switch member fixed to said armature, and a thumb piece mounted for rotary movement in a fixed plane and provided with means for operatively engaging said movable switch member only when in unretracted position. 40
- In witness whereof, I have hereunto set my hand this 12th day of October, 1925.

CARL PAPE.
